WELL PACKER

Martin B. Conrad, Huntington Park, and Ralph K. Matlack, Maywood, Calif., assignors to Baker Oil Tools, Inc., Vernon, Calif., a corporation of California

Application March 11, 1949, Serial No. 80,837

8 Claims. (Cl. 166—10)

1

The present invention relates to well packers adapted to be set in open well bores, as well as in casings, liners and similar conduits disposed in well bores.

An object of the invention is to provide a well packer embodying a packing structure which, when expanded outwardly against the wall of a confining enclosure, is capable of resisting displacement upon being subjected to substantial pressures, and without the necessity for employing supplementary gripping devices, such as slips and the like.

Another object of the invention is to provide a well packer embodying a packing structure capable of effectively anchoring itself to the wall of the formation in open hole, or wall of a well conduit, in order to resist longitudinal displacement when subjected to substantial pressures in the well bore.

A further object of the invention is to limit positively the extent to which the packing structure of the well packer can be expanded outwardly.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figs. 1 and 1a together constitute a longitudinal section through a well apparatus disposed in a well bore, with the parts occupying their relative positions for lowering the equipment in the well bore, Fig. 1a forming a lower continuation of Fig. 1;

Fig. 2 is a view similar to Fig. 1a of the well packer expanded against the wall of the well bore;

Fig. 3 is a cross-section taken along the line 3—3 on Fig. 1a;

Fig. 4 is an enlarged fragmentary section of the locking device employed in the well packer;

Fig. 5 is an enlarged fragmentary, longitudinal section through the lower portion of the packing structure forming part of the well packer, disclosed in its initial retracted condition;

Fig. 6 is a view similar to Fig. 5 of the well packer after expansion of its packing structure against the wall of the well bore;

2

Fig. 7 is a partial longitudinal section through the expanded well packer within a well conduit, such as a casing section.

The well packer A disclosed in the drawings includes a central, generally cylindrical body 10 having a lower guide and abutment 11 threadedly secured to its lower end. A packing sleeve 12 of rubber or rubber-like material is disposed around the body, with its lower end resting upon an upwardly extending annular boss 13 of the lower abutment. The upper end of the packing sleeve engages a corresponding boss 14 extending downwardly from an upper abutment 15 that is slidably downwardly along the body 10.

The packing sleeve 12 is made of natural or synthetic rubber and the like, and is capable of being expanded outwardly against the wall of a confining enclosure, such as the wall of a well formation B. Such expansion occurs as the result of downward movement of the upper abutment 15, and relative upward movement of the body 10 and its lower abutment 11, in order to foreshorten the packing sleeve 12 and effect its outward expansion against the wall of the confining enclosure.

The packing sleeve 12 initially has substantial clearance with the wall of the confining enclosure, to insure its unimpeded lowering through the well bore to the desired point at which it is to be set therewithin. In order to prevent cold flowing of the rubber packing material through the clearance spaces 16 existing between the upper and lower abutments 15, 11 and the confining well bore, flow preventing rings or bridging members 17 are disposed at opposite ends of the packing sleeve. These rings may be made of suitable material, such as rubber that is substantially harder than the packing sleeve. Each ring 17 is seated within a recess 18 provided by the boss 13 or 14, and is centered by engaging the periphery of the boss. Its periphery is initially substantially cylindrical, whereas its inner surface 19 is inclined, engaging a companion inclined inner surface 20 at the end of the packing sleeve. This sleeve also has a shoulder 21 at each end engaging the small end 22 of the tapered ring 17.

The direction of taper of the upper ring surface 19 and the inclined surface 20 at the upper end of the packing sleeve 12 is upwardly and inwardly, whereas the direction of taper of the lower ring surface and the lower inclined surface of the packing sleeve 12 is in the opposite direction. In other words, the rings 17 and the ends 20 of the packing sleeve are alike, although oppositely disposed with respect to one another.

During expansion of the packing sleeve 12 against the formation, the movable abutment 15 is shifted relatively toward the lower abutment 14 fixed on the body. Such action foreshortens the packing sleeve and deforms the packing rings 17 outwardly against the wall of the formation, bridging the clearance spaces 16 between the abutments and the formation wall. At the same time, the packing sleeve 12 is expanded against the formation wall, as is clear from Fig. 2.

The packing is held in such expanded condition by a lock device including a split, inherently contractile sleeve 23 disposed within the abutment 15 and having internal annular ratchet teeth 23 adapted to engage the periphery of the body 10. The sleeve is also provided with external teeth 24 possessing back cam faces 25 engageable with the companion cam faces 26 on internal teeth 27 formed within the movable abutment member 15. The exterior 28 of the body 10 may be roughened, if desired, to insure gripping of the ratchet teeth 23a against the body.

The internal ratchet teeth 23a on the sleeve face upwardly in order to grip the body 10 and prevent upward movement of the movable abutment 15 along the body; or, conversely, relative downward movement of the body 10 within the abutment. The cam faces 25, 26 slope in an upward and outward direction, in order that any tendency for the abutment 15 to move upwardly, or the body 10 downwardly, will cause the cam faces to engage and press the ratchet teeth 23 more firmly into engagement with the roughened exterior 28 on the body, thereby precluding movements in the directions referred to.

The cam teeth 25, 27 and ratchet teeth 23 may be formed conveniently as buttress types of threads, since a machining operation can be performed readily with a thread cutting lathe. The roughened exterior of the body may be formed by cutting shallow, downwardly facing ratchet teeth 28 that may also be formed as a buttress type of thread having the same pitch as the internal thread 23 of the lock sleeve 22.

The lock device constitutes a one-way coupling permitting relative downward movement of the upper abutment 15 along the body 10, in order to expand the packing sleeve 12 outwardly against the formation B. Once such expansion occurs, the lock device prevents return movement of the movable abutment 15 in an upward direction, or downward movement of the body 10 within the movable abutment, insuring the retention of the packing sleeve 12 in its expanded condition.

In the event that the diameter of the open hole in which the packer A is to be set is too great, it is desired to avoid setting the packer in such portion of the open hole. This is done by limiting the extent to which the packing sleeve 12 can be expanded.

As shown in the drawings, a tubular stop member 30 is disposed around the lower portion of the body 10, and rests upon the lower abutment boss 13 within the packing sleeve. This tubular member extends only partially upwardly along the body; so that movement of the upper abutment 15 along the body toward the lower abutment 14 is limited by its engagement with the upper end of the tubular stop member. In this manner, a definite limit is placed upon the degree to which the packing sleeve 12 can be foreshortened, and the extent of its radial expansion.

When expanded against the formation, the packing sleeve 12 will resist displacement as a

result of pressure or other forces imposed upon it from above, or from below. In order to increase its resistance to such displacement, a circumferential groove 31 is formed at each end portion of the packing sleeve a short distance from the flow preventing ring 17. This groove is of V-shape, being defined by a transverse outer shoulder 32 and an inner inclined base portion 33. The shoulder surface is displaced a short distance from the flow preventing ring 17, to provide an elastic flange 34.

It is to be noted that the grooves 31 at the end portions of the packing sleeve 12 are alike, but that they are oppositely arranged. Thus, the sloping face 33 of the upper groove is tapered in an upward and inward direction, whereas the sloping face of the lower groove is tapered in a downward and inward direction.

It has been found that when the packing sleeve 12 is foreshortened and expanded against the wall of the formation, the V-shaped groove 31 is closed by the elastic rubber material of which the packing sleeve 12 is formed. The rubber material 12a in the sleeve on the sloping face side of the groove 31 flows around the exterior of the flange portion 34 of the sleeve, and becomes tightly clamped between this flange portion and the wall of the formation, or other confining enclosure. This condition is exemplified in Fig. 6. This wedging of the rubber packing material 12a between the packing flange portion 34 and the formation wall greatly increases the resistance of the set packer to longitudinal displacement, and, accordingly, requires a much greater pressure to force the set packer longitudinally along the hole. Actual demonstrations have proved this to be the case, since the packing sleeve 12 provided with the grooves 31 required much higher pump pressures to effect longitudinal displacement of the well packer than packing sleeves without the grooves formed therein.

The effectiveness of the grooved packing sleeve is so pronounced as to enable the packer to be set in a well conduit, such as a well casing C (Fig. 7). Despite the fact that the inner wall surface of such a well conduit is relatively smooth, the packing sleeve 12 still becomes anchored to the casing tenaciously. It cannot be displaced unless subjected to substantial pressures. As in the setting of the well packer in open hole, the packing material 12a on the inner side of each groove 31 tends to flow around the packing flange or end portion 34, and becomes wedged between such portion and the wall of the well casing C, providing a greater friction force between the packing structure and the well casing, and requiring much greater pressures to displace the well packer than was heretofore necessary.

The well packer A can be set in several ways, so long as the upper abutment 15 is movable downwardly and the packer body 10 shifted upwardly with respect to each other. As shown in the drawings, the packer is run in the well bore by means of a wire line D, and is set in the well bore by a setting tool E.

The setting tool E includes a cylinder 36 having upper and lower heads 37, 38 threaded into the opposite ends of a cylinder sleeve 39. The upper head 37 is threaded onto a cable head 40 secured to the wire line D in a known manner. Also threaded into the cable head is a gun barrel 41 having a blank cartridge 42 connected electrically to the conductive core 43 of the wire line. This cartridge 42, when fired, ignites the upper end of a combustible charge 44, such as a railway

flare, disposed within a combustion chamber 45 in the upper head 37. The combustible charge generates gases under pressure within the cylinder 36, forcing a piston 46 downwardly within the cylinder, or reactively elevating the cylinder itself. This piston is secured to a depending piston rod 47 extending through the cylinder head 38 and into an elongate tubular mandrel 48 threaded into the lower head 38. The lower end of this mandrel is threadedly secured to a coupling sleeve 49, that has an adapter 50 secured to it into which the upper end of a disruptable tension stud 51 is threaded. The lower end of this tension stud is threaded into the upper end of the packer body 10. The tension stud has a reduced diameter medial portion 52, to insure pulling apart of the stud at this point when the ultimate load capacity of the stud in tension is exceeded.

The piston rod has a cross-piece 53 mounted in its lower slot 54, which extends in opposite directions from the rod through aligned elongate slots 55 in the tubular mandrel 48. The cross-piece extends beyond these slots and into aligned slots 56 in a setting ring 57, on which the upper end of a setting sleeve 58 is threadedly secured. This setting sleeve extends downwardly along the mandrel and has an adapter ring 59 secured to its lower end, to which an adapter sleeve 60 is attached, as by use of welding material 61. The lower end of this adapter sleeve 60 bears upon a shoulder 62 of the movable abutment member 15.

Leakage from and into the cylinder 36 is prevented by the seal rings 63; whereas leakage along the piston 46 is prevented by the piston rings 64.

The well packer A, with its parts in retracted position, is secured to the setting tool E, and this combination is lowered on the wire line D within the well bore or casing to the desired setting point. When such point is reached, the blank cartridge 42 is fired electrically to ignite the upper end of the power or combustible charge 44. Burning of this charge exerts a downward force on the piston 46 and piston rod 47, shifting them downwardly within the cylinder 36 and also moving the cross-piece 53, setting ring 57, setting sleeve 58, adapter ring 59 and adapter sleeve 60 in a downward direction. Such downward movement first disrupts a shear pin 65, holding the upper abutment 15 to the body 10, and shifts the upper abutment downwardly, as permitted by ratcheting of its lock sleeve 22 downwardly over the body 10, toward the lower abutment 11, in order to foreshorten the packing sleeve 12 and expand it outwardly against the well bore or confining casing, in the manner described above.

The pressure in the cylinder continues to increase, as the result of continued combustion of the charge 44, urging the piston 46 downwardly with a greater force, and moving the cylinder 36 relatively upwardly. As described above, the piston 46 exerts its force downwardly upon the packing sleeve 12 through the piston rod 47, cross-piece 53, setting ring 57, setting sleeve 58, adapter ring 59, adapter sleeve 60 and upper abutment 15. The cylinder 36 exerts an upward force on the packing sleeve 12 through the tubular mandrel 48, tension stud 51, packer body 10 and the body abutment 11. Thus, the upper abutment 15 and lower abutment 11 are urged toward one another with an increasing force, as the power charge generates gas under pressure, packing the sleeve 12 more securely between the body and the confining well bore or casing.

When the tensile strength of the stud 51 is ex-

ceeded, upon increase in the pressure within the cylinder to a value corresponding to the ultimate strength of the tension stud, the latter will be pulled apart at its reduced diameter portion 52, automatically releasing the setting tool E from the well packer A. The setting tool may now be removed from the well bore by elevating the wire line D.

Following release of the setting tool E from the packer A, the latter will remain locked in its packed-off condition. Such locking action is assisted by the wedging of the packing material 12a behind the flanges 34 at the end portions of the packing sleeve 12. Movement of the abutments 11, 15 away from one another is prevented by the one-way ratchet sleeve 22.

The inventors claim:

1. In a well packer: a body; a packing sleeve disposed around said body; means for expanding said packing sleeve outwardly; said packing sleeve having an exposed external generally V-shaped circumferential groove in one of its end portions, an abutment engageable with said one end portion, the side wall of said groove toward said one end portion being transverse of the sleeve axis, and the side wall of said groove toward the central portion of said packing sleeve being inclined to said other side wall in a lateral outward direction leading away from said end portion.

2. In a well packer: a body; a packing sleeve disposed around said body; means for expanding said packing sleeve outwardly; said packing sleeve having an exposed external generally V-shaped circumferential groove in each of its end portions, said grooves being adapted to be closed by said packing sleeve upon its outward expansion; an abutment engageable with each of said end portions; the side wall of each groove toward its adjacent end portion being transverse of the sleeve axis, and the side wall of each groove toward the central portion of the packing sleeve being inclined to said other side wall, said inner side walls of said grooves converging toward each other.

3. In a well packer: a body; a packing sleeve disposed around said body; a first abutment on said body engageable with one end of said sleeve; a second abutment slidably along said body toward the first abutment and engageable with the other end of said sleeve; said packing sleeve having an exposed external generally V-shaped circumferential groove in one of its end portions; the side wall of said groove toward said one end portion being transverse of the sleeve axis, and the side wall of said groove toward the central portion of said packing sleeve being inclined to said other side wall in a lateral outward direction leading away from said end portion.

4. In a well packer: a body; a packing sleeve around said body; a first abutment on said body having a boss engageable with one end extremity of said sleeve; a second abutment slideable along said body toward said first abutment and having a boss engageable with the other end extremity of said sleeve; a deformable ring on each abutment encompassing its boss, said ring having an inner tapered surface engageable with a companion tapered surface on said packing sleeve; said packing sleeve having a circumferential groove adjacent each ring and spaced longitudinally inwardly therefrom, each of said grooves having a side wall toward its adjacent ring transverse of the sleeve axis, the side wall of said groove toward the central portion of said

75

packing sleeve being inclined to said other side wall.

5. In a well packer: a body; a packing sleeve around said body; a first abutment on said body having a boss engageable with one end extremity of said sleeve; a second abutment slidible along said body toward said first abutment and having a boss engageable with the other end extremity of said sleeve; a deformable ring on each abutment encompassing its boss, said ring having an inner tapered surface engageable with a companion tapered surface on said packing sleeve; said packing sleeve having a circumferential groove adjacent each ring and spaced longitudinally inwardly therefrom, each of said grooves having a side wall toward its adjacent ring transverse of the sleeve axis, the side wall of said groove toward the central portion of said packing sleeve being inclined to said other side wall; and a tubular member disposed around said body within said packing sleeve and engageable with both abutments to limit the approach of said abutments toward each other.

6. In a well packer: a body; a packing sleeve around said body; a first abutment on said body having a boss engageable with one end extremity of said sleeve; a second abutment slidible along said body toward said first abutment and having a boss engageable with the other end extremity of said sleeve; a deformable ring on each abutment encompassing its boss, said ring having an inner tapered surface engageable with a companion tapered surface on said packing sleeve; said packing sleeve having a circumferential groove adjacent each ring and spaced longitudinally inwardly therefrom, each of said grooves having a side wall toward its adjacent ring transverse of the sleeve axis, the side wall of said groove toward the central portion of said packing sleeve being inclined to said other side wall, said inclined side walls of said grooves converging toward each other.

7. In a well packer: a body; a packing sleeve around said body; a first abutment on said body

having an annular boss engageable with one end extremity of said sleeve; a second abutment slidible along said body toward said first abutment and having an annular boss engageable with the other end extremity of said sleeve; and a deformable ring on each abutment encompassing its boss, said ring having an inner tapered surface engageable with a companion tapered surface on said packing sleeve.

8. In a well packer: a body; a packing sleeve around said body; a first abutment on said body having a boss engageable with one end extremity of said sleeve; a second abutment slidible along said body toward said first abutment and having a boss engageable with the other end extremity of said sleeve; a deformable ring on each abutment encompassing its boss, said ring having an inner tapered surface engageable with a companion tapered surface on said packing sleeve; said packing sleeve having an exposed circumferential groove adjacent each ring and spaced longitudinally inwardly therefrom, each of said grooves having a side wall toward its adjacent ring transverse of the sleeve axis, the side wall of said groove toward the central portion of said packing sleeve being inclined to said other side wall, said inclined side walls of said grooves converging toward each other.
